UNITED STATES PATENT OFFICE.

EDWARD C. LORENTZEN, OF SCRANTON, IOWA.

DRESSER FOR SUITCASES.

Application filed June 19, 1923. Serial No. 646,328.

The object of my invention is to provide a dresser of simple, durable and inexpensive construction, adapted for the reception of suit cases, and for holding the suit case in suitable position for opening, or for displaying, or using the contents of the suit case.

A further object is to provide such a device having a drawer or drawers capable of being mounted to various heights with relation to the floor on which the dresser rests, and also with relation to each other for accommodating them to suit cases of different sizes.

Still a further object is to provide a dresser of the kind mentioned having drawers equipped with stop devices which are detachable and may be yieldingly held in operative position to prevent the entire removal of the dresser drawer from the dresser when the drawer is drawn out to receive a suit case, or to permit the user to have access to the contents thereof, which stop device is also capable of being moved to an operative position for the entire removal of the drawer when necessary.

My invention consists in the construction, arrangement and combination of the various parts of the device, whereby the objects contemplated are attained, as hereinafter more fully set forth, pointed out in my claim, and illustrated in the accompanying drawings, in which:

Figure 1 shows a front elevation of a dresser for suit cases embodying my invention.

Figure 2 shows a side elevation of the same.

Figure 3 shows a vertical, sectional view taken on the line 3—3 of Figure 1;

Figure 4 shows a horizontal, sectional view taken on the line 4—4 of Figure 3.

Figure 5 shows a vertical, sectional view of a portion of a dresser and a rear elevation of one of the drawers in view being taken on the line 5—5 of Figure 3; and

Figure 6 shows a perspective view of one of the drawers.

In the accompanying drawings, I have used the reference numeral 10 to indicate generally the upright corner members which are found at the four corners of and form a part of the frame of my improved dresser. The two rear corner posts 10 are longer

than the front posts and support between them the frame members 11 which carry the mirror 12.

My improved dresser is provided with the ordinary top 13. The upright members 10 at each end of the dresser are provided with panel members 14 at the upper and lower ends of the dresser. The upper and lower panel members 14 at each end of the dresser are connected by upright panel members 15.

Secured to the inner surface of the members 10 at each end of the dresser is a plurality of horizontal shelf supporting members 16, arranged to be in regular vertical succession equally spaced apart at each end of the dresser. The members 16 at one end of the dresser are arranged to be opposite the respective members 16 at the other end of the dresser.

I have provided shelves or drawers of somewhat peculiar construction for the reception and display of suit cases, each comprising a front upright member 17 having a notch 18 permitting the suit case handle to project through. Each drawer or shelf has a bottom preferably made of spaced slats 19. Each side of each drawer is made up of spaced pairs of slats 20. The space between the slats 20 at each side of the drawer is such as to properly receive between said slats one of the members 16 for permitting the drawer to slide freely. The parts are so arranged that the front 17 fills the space between the two front members 10, and when the drawer is pushed inwardly 90 engages the members 16 between the slats 20 at each end of the drawer for limiting the inward movement of the drawer.

Near the back of each drawer is a back member 21, resting upon the bottom members 19, and secured to the side members 20 for properly supporting them in position.

Mounted on the rear surface of the back member 21 is a bracket and bearing member 22, rotatively mounted on which is a disc 23 having an upwardly projecting handle 24. Pivoted off center on the opposite sides of the disc 23 are opposite laterally extending rods 25, one of the rods 25 extending slidably through a suitable opening in the upper member 20 on one side of the dresser, and the other member 25 extends slidably through the other member 20 on the other

side of the dresser. The members 25 form locking members and are normally held at their outward limit of movement by means of a spring 26 secured to one of the members 25, and to the frame of the drawer.

The parts just described are so arranged that when the members 25 are held at their outer limit of movement, their ends project beyond the members 20, so that they form 10 stop devices for engaging the forward members 10 and limit the outward movement of the drawer for preventing its entire removal from the dresser. It is, however, well known that suit cases are of different sizes, 15 so that it may be necessary to adjust the drawers for arranging them at different heights in the dresser for receiving suit cases of different kinds.

It is also possible, when it is desired to 20 take one of the drawers out of the dresser and put it in again to a lower or higher position by grasping the handle 24 and drawing the members 25 inwardly, withdrawing their outer ends from engagement with the members 10, or from position where such ends would otherwise engage the members 10, and thereby permit the entire removal of 25 the drawer from the dresser. The drawer can then be inserted in a higher or lower 30 place, and upon releasing the handle 24, the spring 26 will cause the ends of the members 25 to project beyond the members 20, forming stop devices for preventing the entire removal of the drawer from the dresser.

35 In the practical use of my improved dresser, for suit cases, it will be understood that my device is designed particularly for use in hotels and the like.

The user may draw one of the drawers 40 out and place his suit case 27 therein. The suit case cover 28 may be raised when the drawer is in its outer position for displaying the contents of the suit case and rendering them accessible to the owner without entirely removing them from the suit case. 45 If the owner has one small suit case and one very large one, the drawers may be readily and easily adjusted at proper heights on the proper members 16 to receive both the suit 50 cases. In this connection it may be noted that the dresser has no front members between the upper and lower front members,

so that the drawers may be adjusted at any desired height.

When the drawers are closed and not in 55 use, they have no projecting parts. When in use the handle of the suit case projects through the notch 18, and by pulling on the handle any drawer may be brought out of the dresser for the removal of the suit case, 60 or displaying the contents.

65 My improved dresser is of extremely simple and inexpensive construction and is adapted for use to suit cases of ordinary size.

70 It will be understood that some changes may be made in the arrangement and construction of my improved dresser for suit cases, without departing from its essential features and purposes, and it is my intention to cover by this application any such changes which may be included within the scope of my claim.

75 I claim as my invention:

A dresser for suit cases comprising a stationary frame having side members, a series of equally spaced horizontally arranged guide devices on said side members, the front of the dresser being open and unobstructed, a series of drawers each comprising a bottom, 80 sides, a front and a rear member, each side member being formed with two spaced bars designed to slidably receive one of the guide devices on the frame, the rear member of the drawer being spaced forwardly from 85 the rear ends of the side members of the drawer, and the front of the drawer being formed with a notch, said parts being so arranged and constructed that they may be inserted on any of the said guide devices 90 and may be adjusted up and down in the dresser to accommodate it for different thicknesses of suit cases, said guide devices and the bars forming the sides of the drawers being so shaped and arranged as to support the drawer in a horizontal position when the drawer is extended out to position with the rear of the drawer substantially flush with the dresser front, and a releasable means for limiting the outward movement 95 of the drawer.

100 Des Moines, Iowa, March 8, 1923.

EDWARD C. LORENTZEN.
